J. A. MANSON,
REVOLVING CARD STAND,
APPLICATION FILED FEB. 8, 1912.

1,049,886.

Patented Jan. 7, 1913.

UNITED STATES PATENT OFFICE.

JOHN A. MANSON, OF BRIDGEPORT, CONNECTICUT.

REVOLVING CARD-STAND.

1,049,886.

Specification of Letters Patent.

Patented Jan. 7, 1913.

Application filed February 8, 1912. Serial No. 676,221.

To all whom it may concern:

Be it known that I, JOHN A. MANSON, a citizen of the United States, and a resident of Bridgeport, in the county of Fairfield and State of Connecticut, have invented a new and Improved Revolving Card-Stand, of which the following is a full, clear, and exact description.

My invention relates to a new and improved revolving card stand, and an object of my invention is to provide a stand more particularly adapted to carry display cards such as is described in full in my copending application, Serial No. 663,079, filed November 29, 1911.

An object of my invention is to provide a revolving stand so constructed that the display cards may be readily dismounted and replaced.

With the above and other objects in view as will more fully hereinafter appear, the present invention consists in certain novel details of construction and arrangement of parts hereinafter described and particularly set forth in the appended claims.

Reference is to be had to the accompanying drawings, forming a part of this specification, in which similar characters of reference indicate corresponding parts in all the figures, and in which—

Figure 1 is a perspective view showing a preferred embodiment of my invention; Fig. 2 is an enlarged vertical sectional view taken through the device shown in Fig. 1, a central portion thereof being broken away, and Fig. 3 is a transverse sectional view taken on the line 3—3 of Fig. 1 and looking in the direction of the arrow.

Described more in detail, my invention comprises a relatively broad flat hollow base 4. Extending vertically through the base 4 and fastened to the under side thereof by a nut 5, is a rod 6, the upper portion above the base being an enlarged steel bearing spindle 7, brazed to the lower end of which is a bronze stop bushing 8, having a flanged rim 9, resting upon which flanged rim is a long tube 10. The end of the steel bearing spindle 7 has a conical top 11, which conical top is rotatably mounted in a bronze bearing plug 12. By this construction the tube 10 is rotatably mounted upon the base 4. To prevent the withdrawal of the spindle 7 from the tube 10, the spindle 7 has a peripheral groove 13 in alinement with the upper end of the bushing 8, in which groove

is disposed a split stop ring 14. The stop ring is supported on the tube 10 and in assembling the parts the conical end of the spindle 7 readily passes through said ring, so as to bring the groove and stop ring into register with each other.

Rigidly positioned on the tube 10, a slight distance above the rim 9, is a lower plate 15, which lower plate has a series of apertures 16 disposed adjacent the outer edge, which apertures are adapted to receive the lower pins 17 of card plates 18. A similar plate 19 is disposed adjacent the top of the tube 10, which plate also has apertures 20 adapted to receive the upper pins of the card plates 18. These card plates 18 are inserted on the stand by passing the upper pins on the card plates into the apertures 20, and then inserting the lower pins into the apertures 16. The card holders are locked in position by means of a dome plate 21, which plate is slidably mounted on the tube 10 above the plate 19. This dome plate is hollow and its outer edge rests, when in locking position, upon the outer edge of the plate 19, and either bears upon or is positioned a short distance above the end of the upper pins of the card holder, so that the lower pins can not be displaced from the apertures 16 unless the dome plate is raised into unlocking position, as shown in dotted lines in Fig. 2. The dome plate has a sleeve 22 projecting therefrom and surrounding the tube 10, which sleeve 22 has a diagonal bayonet slot 23, disposed in which slot is a pin 24 projecting from the tube 10.

It will be seen by this construction, that rotating the dome plate 21 in one direction will raise or lower the same into unlocking or locking position. An ornamental knob 25 surmounts the top of the tube 10, to give a finished appearance to the tube, and may also be used as a limiting stop for the dome plate 21.

Having thus described my invention, I claim as new and desire to secure by Letters Patent:

1. A card stand, comprising a tube, an apertured plate carried by said tube adjacent its upper end, a hollow dome plate slidably mounted on said tube above said plate, the outer edges of said dome plate when in locked position resting on the outer edge of said apertured plate, said dome plate having a sleeve projecting upwardly therefrom and surrounding said tube, said sleeve hav-

ing a diagonal bayonet slot therein, and a pin projecting from the tube and engaging said slot, to lock the dome plate in position on said apertured plate.

- 5 2. A card holder comprising a tube, upper and lower plates carried by said tube adjacent its ends, each plate having a series of apertures extending therethrough, a card plate having pins projecting from the upper 10 and lower edges thereof and adapted to be inserted within apertures in said plates, and

a hollow dome slidably mounted on said tube above said upper plate, said dome normally resting on said plate and spaced from said upper pin so as not to bear on the same. 15

In testimony whereof I have signed my name to this specification in the presence of two subscribing witnesses.

JOHN A. MANSON.
